UNITED STATES PATENT OFFICE.

ELMER J. RAMBO, OF FINDLAY, OHIO.

DESIGN FOR A LAMP-CHIMNEY.

SPECIFICATION forming part of Design No. 20,183, dated September 30, 1890.

Application filed August 22, 1890. Serial No. 362,777. Term of patent 14 years.

To all whom it may concern:

Be it known that I, ELMER J. RAMBO, a citizen of the United States, residing at Findlay, in the county of Hancock and State of Ohio, have invented and produced a new and original Design for Glass Lamp-Chimneys, of which the following specification is a full, clear, and exact description.

This design while having reference more particularly to the tops of glass chimneys for lamps may be applied to other like hollow articles of glassware, and is included for the several uses to which it may be adapted.

In the accompanying drawings, which form part of this specification, Figure I is a partial view of a lamp-chimney, in elevation, showing the present design; and Figs. II, III, and IV are partial views of the top on a much enlarged scale, Fig. II being an elevation and Figs. III and IV vertical sections on lines iii and iv, looking in the direction of the arrows.

The leading features of my design consist of an open flared top A of appropriate angle and an overhanging toothed crown of block-like projections B of about equal height, depth, and width, with flattened lateral faces 2, with the front faces 3 convexly rounded both vertically and horizontally, with the under faces 4 concave, and with a reversed curved bead 5 extending out from the supporting plain surface 6 horizontally under each of the oblique division-lines 7 at the junction of the adjacent flattened lateral faces 2, the greatest diameter, as indicated by the dotted

line 8, being about midway of the height of 35 the crown, which is cleft below said line of greatest diameter. The continuation of the surface 6, it will be observed, would cut off a large part of the blocks, as indicated by the dotted line 9.

The overhanging crown of block-like teeth with flattened, convex, and concave sides gives a peculiarly neat and light ornamental appearance to the top of the chimney. Being made of glass, the light is transmitted and reflected 45 very variably by the different faces 2 3 4 of the block-like teeth B and the reversed bead 5, so as to impart a novel and pleasing effect. As shown, the crown is composed of thirty-eight blocks or teeth B, and the depth (measured on the dotted line 10) is a little less than 50 or only approximately equal to the height and width, (measured along the dotted lines 11 and 12,) which are also slightly unequal. In Figs. I and II the height appears somewhat 55 foreshortened. As shown further, the oblique division-lines 7 make an acute angle with the extensions of the plain surface 6.

What I claim is—

The design for lamp-chimneys herein shown 60 and described.

In testimony whereof I have signed this specification in the presence of two witnesses.

ELMER J. RAMBO.

Attest:

FRANKLIN FRANKS,
V. T. SPITLER.
